W. Humphrey
Carding Mach.

Patented Oct. 4, 1811.

Second Part

The second part of the paper is in these letters dated and making part of the same, containing a description in the words of the said William Humphreys himself of his new Machine for Drawing and Spinning Wool, called the Humphreysville Appliance.

The machines for drawing and spinning are composed of rollers, a description of which is as follows viz:

The wool from the carding machine, passes through the back roller which connects it to the card or tooth roller by the assistance of another small roller which induces it to the teeth of the tooth or card roller. From the tooth roller it is drawn to any size that may be required by a pair of feed rollers coupled together and weighted, either by reflecting the operations through the same or other machines upon the same principle, or by increasing the velocity of the front rollers.

The principle is, the front rollers draw the wool off the wool through the teeth of the card or tooth roller, as the case may require. The card or tooth roller or rollers retain the bulk of the wool, drawing or drawing, and, draw it perfectly even to the front rollers, which reduce it to any size required by repeated operations.

The dimensions of the rollers & gearing may be altered as circumstances may require.

The object of this machine is to take the wool either in rolls or in bales from the carding machine as may be deemed most expedient, and reduce it to a size suitable to be spun into thread, as may be required.

15000

upon the body of a cotton or woolen material, accompanied by a roller which runs upon the cotton, except in the instance, size of rollers, the card or two rollers between the front and back rollers.

Appendix

I extend the principles of the above to the drawing spinning of all the various substances of wool, woolen, sheep, flax & cotton, by varying the size of the card in proportion to the article of the article. also the usual process of a gig bobbin, which contains no rovings & serves for the purpose of drawing them out of the rovings, before it enters the back road of the machine, which has the tendency to pull them, and makes it by the draft of the front roller to draw more easily and pliable through the teeth of the card or both rollers than it otherwise would.

The machinery for preparing and spinning the silk and other articles, will be the same same in principle, as the former specification for wool, but different as to their sizes & the several proportions of their various parts.

The principles of the machinery are calculated to take the raw materials either from the card or roller or bing or from the back road of the article of flax. to prepare it in according with spin it into yarn upon different machines upon the same principles.

Woolen rovings prepared for a card

an iron hand-wheel, will regulate the progress
equally well to be open on this plan as is done
now by a machine by means of this plan
of 16 spindles now in operation.
